UNITED STATES PATENT OFFICE.

JOHN POWELL, OF KIDDERMINSTER, ENGLAND, ASSIGNOR TO HENRY JECKS
DIXON & SONS, OF SAME PLACE.

DESIGN FOR CARPET.

Specification forming part of Design No. 6,784, dated July 22, 1873; application filed June 13, 1873.

To all whom it may concern:

Be it known that I, JOHN POWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

The design represents a garden scene with trees, vines, flowers, arches, &c., as shown in the photographic illustration.

I claim as my invention—

The design for carpets, as shown.

JOHN POWELL.
